CONTROL DEVICE

**Earnest J. Dillman, Detroit, Mich., assigner to
Detroit Lubricator Company, Detroit, Mich., a
corporation of Michigan**

Original application September 12, 1936, Serial
No. 100,476. Divided and this application
March 10, 1937, Serial No. 129,981

3 Claims. (Cl. 137—104)

This application is a division of my copending application, Serial No. 100,476, filed September 12, 1936, for Control devices.

One of the objects of my invention is to provide a control device of new and improved construction for controlling electric circuits.

Another object of my invention is to provide a control device responsive to changes in liquid level and one having a new and improved arrangement of the operating parts thereof.

Another object of my invention is to provide for a heating system having a boiler for water, a new and improved liquid level control device including a float which will not be subject to surging action of the boiler water.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated my invention, in which drawings—

Figure 1 is a diagrammatic view of a heating system embodying my invention;

Fig. 2 is an enlarged view shown partly in cross section and partly in elevation of a control device employed in the system of Fig. 1 and embodying features of my invention;

Fig. 3 is a view shown in cross section taken along the line 3—3 of Fig. 2;

Fig. 4 is a view of my control device shown partly in elevation and partly in section, taken along the line and in the direction of the arrows 4—4 of Fig. 3; and

Fig. 5 is a detail view showing the means for securing together the end and side walls of the control device casing.

Referring to the drawings and first to Fig. 1, there is shown a heating system which includes a boiler 1 and a heat supplying means therefor which may be a fuel stoker or oil burner preferably operated by an electric motor 2. The system also includes a water supplying means of which only the water supply pipe, indicated at 3, is shown and through which pipe water is supplied to the boiler 1 when necessary. In the water supply pipe 3 there is provided a control device 4 for controlling flow of water to the boiler, and also in the pipe 3 there may be provided a strainer, indicated at 5, preferably located as shown between the source of water supply and the control device 4. The control device 4 may be of any suitable type and is preferably an electrically operated device such as a solenoid valve.

In the present instance, the valve of the control device 4 is opened permitting flow of water to the boiler 1 when the solenoid is energized, and closed upon deenergization of the solenoid to stop flow or admittance of water to the boiler. A by-pass pipe 6 is provided in the feed pipe 3 for bypassing water around the solenoid valve 4 to the boiler 1, and flow through the by-pass pipe 6 may be controlled by a hand operated valve 6^a, the purpose of the by-pass being hereafter described.

The heating system also includes a control device, designated in general by the numeral 7, which in the present instance is a float actuated control. The float, indicated at 8, is operable in response to changes in the level of the water in boiler 1 to control the operation of both the burner motor 2 and the water supply control device or valve 4. Associated with the float mechanism there is provided a switch means, 20 designated in general by the letter B and a second switch means designated in general by the letter C, both of which are actuated by the float 8 to control actuation of the solenoid valve 4 and burner motor 2, respectively. The burner motor 2 may be operated from the usual 110 v. line to which 110 v. line are connected lead wires 11, 12 in which there may be provided a manually operable switch 13. A control device, preferably a relay indicated at 14^a, is provided in the circuit 30 of the motor 2, and the relay 14^a may be connected to the motor 2 by lead wires 14 and 15. The switch means C is in series circuit with the burner motor 2 by means of the lead wires 15^a and 16, the switch means C is operable to control 35 the operation of the motor 2. The switch means B is operatively connected in parallel circuit with the burner motor 2 by means of a lead wire 17 connected to lead wire 12, and a lead wire 18 connected to lead wire 16 of the switch means C. 40 Connected between the lead wires 17, 18 there is preferably provided a transformer 19 to provide low voltage current for operation of the solenoid valve 4. The switch means B is connected to one side of the secondary of the transformer 19 45 by the lead wire 19^a, and is connected to the other side of the transformer secondary by the lead wire 19^b, the solenoid valve 4 being connected in the lead wire 19^b between the transformer 19 and the switch means B. Thus, since the solenoid 50 valve 4 is in parallel circuit with the burner motor 2, the solenoid valve 4 as well as the motor 2 will be deenergized when the circuit is opened to the motor by means of switch means C. The numeral 20 designates a room thermostat con- 55

nected to the relay 14^a to cut in and cut out the motor 2 to maintain a predetermined room temperature, and the thermostat 20 may be connected to the relay 14^a by the lead wires 9 and 10.

In the system shown in Fig. 1 the float mechanism and the associated switch means B and C are mounted on a wall of the boiler 1 with the float 8 projecting into the interior of the boiler. Referring now to Figs. 2, 3 and 4 in which the detail construction of the float mechanism and the associated switch means B and C are shown, the structure includes a supporting means in the form of a plate 21 which is fixed to the outer wall surface of the boiler 1 by means of bolts or other suitable means. The plate 21 closes an opening in the wall of the boiler 1, which opening is provided to receive a casing or housing 23 which projects through the opening into the interior of the boiler and encloses the float 8. The casing 23 is constructed, in the present instance, of sheet metal and comprises a shell or sleeve-like member 25 closed at the top by a plate or end member 26 and at the bottom by a second plate or end member 27. The end members 26, 27 have tab portions 26^a, 27^a respectively which extend through apertures 26^b, 27^b respectively in the sleeve-like member 25 so that the portions of the end members furthest away from the plate 21 are located with respect to the sleeve-like member 25. The sleeve or shell 25 is of substantially U-shape in cross section, as shown in Fig. 3. The portions of casing 23 adjacent the plate 21 are formed with outturned flange portions 28 for seating against the inner wall surface of plate 21 which is preferably recessed, as at 29. The end member 26 has an offset portion 29^a which acts to increase the volume of the chamber 29^b defined by the casing 23. Screws 30 or other suitable means may be used for rigidly securing the casing 23 to the plate 21. In a wall of the casing 23 and preferably in a substantially vertical wall thereof there is provided an aperture 32, adjacent the bottom of the casing, and a second aperture 33 adjacent the top of the casing for the passage of water in and out of the float casing in accordance with variations in the liquid level of the water in boiler 1. By providing relatively small apertures in the casing 23 and locating them in a vertical or substantially vertical wall of the casing, water will flow in and out of the casing 23 without the transmission of the motion of the surging boiler water to the water within the casing, and therefore without transmission of such motion to the float 8.

The plate 21 is formed with an outwardly extending protuberance 31 which is in alignment with the casing 23 and which has a centrally disposed opening 32^a therethrough opening through the plate 21 into the float chamber or interior of the casing 23. Mounted on the outer wall of the plate 21 there is a supporting means in the form of a housing which includes an end wall member or bracket 34 which may be in the form of a casting, as shown. The supporting means 34 has an end wall 35 extending substantially parallel to the end wall of the protuberance 31, and extending rearwardly from the wall 35 at the top and bottom thereof are oppositely disposed and substantially parallel flanges 37 and 38, the bracket or supporting means 34 thus having the form of a U-shaped channel member, as shown more clearly in Fig. 2. The U-shaped bracket 34 is preferably recessed along its side edges for receiving the oppositely disposed sides 75 of a three-sided closure member or cover 40.

The cover 40 cooperates with the U-shaped bracket 34 to provide a housing or enclosed space 41, and the cover 40 may be secured to the U-shaped bracket 34 by screws, or by other suitable means.

Through the wall 35 of the supporting means 34 there is provided an opening 43 in alignment with the opening 32^a in the plate 21, and extending through the aligned openings 33 and 32^a and into the housing 41, there is one end of a lever 46, the other end of which is rigidly fixed to the float 8. A movable sealing means is provided for closing and sealing the opening between the housing 41 and the boiler 1, and the sealing means may be a substantially cylindrical, circumferentially corrugated, resilient, metallic bellows 47. The bellows 47 has one end secured and hermetically sealed to a ring-like end wall member 48, which member is tightly clamped between the outer end wall of the protuberance 31 and an extended portion 49 of the wall 35 of the supporting means 34. The outer end wall of the extended portion 49 is recessed providing an outwardly facing annular shoulder or seating surface against which the ring-like end wall 48 of the bellows seats. The outer end wall of the protuberance 31 is formed with a reduced and extended portion which extends into the recess in the wall 35 and bears against the adjacent side of the ring-like end wall 48 of the bellows 47. The supporting means 34 and the plate member 26 may be rigidly secured together by means of screws 50, and the end wall 48 of the bellows may be tightly clamped between the opposed walls of the support 34 and plate 21. The bellows 47 surrounds the float arm 46 and extends into the housing 41, the inner end of the bellows being secured and hermetically sealed to a plate 52 which is centrally apertured to receive a reduced portion of the lever 46, which reduced portion projects through and extends beyond the outer wall of plate 52. A cup-shaped shield 53 in the form of a cap is provided and has a central aperture in its end wall for receiving the reduced end of the lever 46, and this cup-shaped shield 53 surrounds the bellows 47 and extends toward the wall 35 of the supporting means 34.

A yoke or U-shaped bracket 55 is provided and is fixed to the outer end of the lever 46 within housing 41. The yoke 55 has a side or base 56 which extends transverse to the lever 46 and oppositely disposed arms or flanges 57 which extend on opposite sides of the lever and inwardly or toward the float 8. The side 56 of the lever is provided with an aperture between the oppositely disposed sides or flanges 57 for receiving the reduced portion of the lever 46, which portion is threaded for threaded engagement with a nut 58 by means of which the yoke, shield and end wall of the bellows 47 may be tightly clamped against the shoulder formed on the rod by the reduced portion, and thereby be rigidly secured to the end of the lever.

On opposite sides of the bellows 47 are vertically disposed ribs 60 which extend from the wall 35 of the supporting means 34, rearwardly or into the chamber 41. The ribs 60 are formed with outwardly and oppositely extending bosses 61 having aligned apertures for receiving pins 62 for pivotally supporting the yoke 55. In the oppositely disposed sides 57 of the yoke 55, and adjacent the ends thereof, are provided aligned apertures for receiving the pins 62, which pins may be threaded for screw threading into the bosses 61. Preferably the pivot pins 62 are located in

the same horizontal plane as the longitudinal axis of the lever 46 and bellows 47, and preferably at a point substantially midway between the ends of the bellows. By locating the fulcrum of the lever 46 at a point substantially midway between the ends of the bellows 47, the bellows will bend at their natural bending point upon pivotal movement of the lever 46.

5 Mounted on the upper flange 37 of the supporting means 34 is the electric switch means C, and fixed to the underside of the flange 38 is the switch means B. The switch means B and C are similar in construction and are enclosed in casings 65 and 66 respectively. The casings 65 and 66 10 each have an open side which is disposed toward the flanges 38 and 37 respectively, and the flanges form one side of the casings. The casings may be secured to the flanges by screws 67, or by other suitable means. The switch means B and C being 15 the same in structure and operation, a description of one is deemed sufficient. Referring to Fig. 4 in which the switch means C is shown in detail, there is provided within the casing 66, at one end thereof, a supporting means preferably in the 20 form of laterally spaced lugs or brackets 70, only one of which is shown, and which are adjacent to but spaced from the lower edges of the casing. Extending longitudinally within the casing 66 there is an elongated supporting member 71 preferably of electric insulating material which extends from one end, as at 72, between the lugs 70 and is pivotally secured to the lugs 70 by a hinge member 73 of resilient sheet metal which is secured to the lugs 70 by screws 73a.

35 Mounted on the upper side of the hinge member 73 there is a U-shaped, so-called permanent magnet 74. Pivotally secured to the supporting member 71 at its other or free end, there is a contact arm 75. The pivotal connection for the 40 arm 75 is provided by a hinge member 76, such as a plate of resilient sheet metal, riveted or otherwise secured to one end of arm 75 and secured by screws 78 to the end of the supporting member 71. The arm 75 carries a contact member 79 which is fixed to the free end of a leaf spring 80 that is secured to and extends longitudinally of the arm 75. The contact member 79 extends toward the supporting member 71 and 45 cooperates with a contact member 81 secured to the member 71. The contacts 79 and 81 are located between the poles of the magnet 74, which tends to hold the contacts together. The lead wire 15a may be connected to the fixed contact 50 81 and the lead wire 16 to the movable contact arm 75. The wires 15a and 16 lead out of an outlet box 83 formed integral with the casing 66.

The supporting member 71 is provided with a guideway 84 extending transversely therethrough 55 and having its longitudinal axis transverse to the arm 75. In the guideway 84 there is a longitudinally reciprocal actuated or thrust member 85 which projects at its ends from the opposite faces of the supporting member 71. The thrust member 85 is preferably in the form of a rod or pin having its opposite ends pointed or conical in form, and one end of the thrust pin 85 engages or abuts the underside of the contact carrying 60 arm 75 preferably adjacent the fulcrum of the arm 75. The other end of the thrust member 85 is in alignment with and bears against the end of a rod 86, which rod has one end screw threaded into or otherwise suitably fixed to a second rod 75 65 carried by the yoke 55. The rod 87 has one end

bifurcated to receive one of the arms 57 of the yoke 55, and the rod 87 and yoke arm 57 may be pivotally connected together by means of a pin 88 or by other suitable means. The rod 87 is pivoted to the adjacent flange or arm 57 of the yoke 55 at a point between the pivot pin 62 and the transverse connecting side 56. To the other or oppositely disposed flange or arm 57 of the yoke 55 there is secured a bifurcated rod 87a by a pin 88. The rod 87a has screw-threadedly secured thereto a rod 90 which extends therefrom and downwardly through the flange 38 into the casing 65 of the switch means B. The switch means B has a thrust member 91 like the thrust member 85 of switch means C, and which is 15 similarly arranged with the switch mechanism within casing 65 to transmit movement of the float to open or permit closing of the switch. For a more detailed description of the switch mechanism reference may be had to my copending 20 application on electric switches, Serial No. 714,743, filed March 9, 1934, now Patent No. 2,098,181, granted March 2, 1937.

In Fig. 2 of the drawings the normal level of the water in the boiler 1 is indicated by the line 25 A, and below the normal level A there are indicated other levels B', B'', C' and C'' at which levels the control devices operate as hereinafter described: When the level of the water in boiler 1 reaches the level B', assuming that water is 30 being supplied to the boiler, the float will have moved upward and pivoted about its pivot points 62. The yoke 55, being on the other side of the pivot points, will have moved downward and acted through the movable thrust member 90 to open 35 the switch of the switch means B against the force of the magnet opposing the opening of the switch. Upon opening of the switch means B the solenoid 4 is deenergized and permits the valve to close and stop flow of water to the boiler. 40 When the float 8 moves upward and opens the switch of the switch means B, the yoke 55 moves further away from the switch means C and the magnet 74 thereof continues to operate to hold the contacts 79 and 81 together and thus maintain the circuit closed to the burner motor 2, which circuit is as follows: From switch contact 81 through contact 79, switch blade 75, lead wire 15a, lead wire 11, manual switch 13, the source of power, lead wire 12, relay 14a, lead wire 15, motor 2, lead wire 14, relay 14a, lead wire 16 back to the switch contact 81. If for some reason the level of the water in boiler 1 decreases to the level C'', for example because of failure of the water supply or because of sticking of the solenoid valve 4 in closed position, then the float 8 will have descended and pivoted about its points 62 and will have moved the yoke 55 upward against the opposing force of the magnet 74 of switch means C. This 45 operation will open the switch and thus cut out the motor 2 to discontinue the supplying of heat to the boiler. Since the solenoid 4 is in parallel circuit with the motor 2 it will be seen that the solenoid will also be deenergized by opening of the primary circuit of the transformer 19 upon decrease in water level to level C'' so that the valve, if not already in closed position, will move to closed position. Upon resumption of water flow from the source of supply, or correction of the 50 cause of decrease of water in the boiler, water is admitted to the boiler 1 by opening the hand valve 6a in the by-pass line 6. When the water rises to the level C' the float 8, having moved upward, permits the magnet 74 of the switch 55 55

means C to close the circuit to the burner motor means for supplying of heat to the boiler 1. The switch means B being closed by reason of the water level being below the line B', then upon energization of the transformer 19 by closure of switch means C, the solenoid valve 4 will be energized to open the valve, the circuit of the solenoid valve being as follows: From the secondary coil of the transformer 19 through lead wire 19^a, switch means B, lead wire 19^b, and the solenoid valve 4 inserted in the lead wire 19^b back to the other side of the transformer secondary coil. Upon resumption of normal operation of the solenoid valve 4, flow of water through the by-pass line 6 should be discontinued by closing the hand valve to reestablish automatic operation. It will be understood that for all levels above level C' the motor 2 is operating to supply heat to the boiler.

20 What I claim and desire to secure by Letters Patent of the United States is:

1. In a device of the character described, a plate member adapted to be secured to a wall and for covering an aperture through the wall, a sheet metal sleeve member having an open side wall portion and being of substantially U-shaped cross-section, said sleeve member being secured to said plate member so that said open side wall portion is adapted to be closed by said plate member and said sleeve member being adapted to extend through the wall aperture, a pair of end members secured to said plate member and co-operable with the end portions of said sleeve member to define a chamber, a pair of relatively small vertically aligned apertures in a wall of said sleeve member for admission of fluid to said chamber, and actuating means in said chamber.

2. In a device of the character described, a plate member adapted to be secured to a wall and for covering an aperture through the wall, said member having a recessed portion adapted to overlie the wall aperture, a sheet metal sleeve member having an open side wall portion and being of substantially U-shaped cross-section, said sleeve member having an outturned flange portion adjacent said open side wall portion,

recessed portion so that said plate member is adapted to close said side wall portion, a pair of end members secured to said plate member and co-operable with the end portions of said sleeve member to define a chamber, one of said end members having an offset portion acting to increase the volume of said chamber, a pair of relatively small vertically aligned apertures in a wall of said sleeve member for admission of fluid to said chamber, and actuating means in said chamber, said offset portion also acting to receive said actuating means.

3. In a device of the character described, a plate member adapted to be secured to a wall and for covering an aperture through the wall, said member having a recessed portion overlying the wall aperture, a sheet metal sleeve member having an open side wall portion and being of substantially U-shaped cross-section, said sleeve member having an outturned flange portion adjacent said open side wall portion, means for securing said flange portion to said recessed portion so that said plate member closes said side wall portion, a pair of end members, each end member having a tab portion at one end thereof and a flange portion at the other end thereof, said end members being secured to said plate member and substantially fitting one within each of the end portions of said sleeve member, said cylindrical member having a pair of apertures, one of said pair of apertures being in one end portion of said sleeve member and the other of said pair of apertures being in the other end portion of said sleeve member, one of said tab portions being received by said one aperture and the other of said tab portions being received by said other aperture to thereby locate said tab portions and said end members with respect to said sleeve member, said end members and said cylindrical member cooperating to define a chamber, a pair of relatively small vertically aligned apertures in a wall of said sleeve member for admission of fluid to said chamber, and actuating means in said chamber.

EARNEST J. DILLMAN. 45
